UNITED STATES PATENT OFFICE.

PITT H. HERBERT, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

OPHTHALMIC MOUNTING.

1,347,462.

Specification of Letters Patent.

Patented July 20, 1920.

Original application filed August 1, 1917, Serial No. 183,950. Divided and this application filed May 2, 1919. Serial No. 294,214.

To all whom it may concern:

Be it known that I, PITT H. HERBERT, of Southbridge, in the county of Worcester and State of Massachusetts, have invented 5 certain new and useful Improvements in Ophthalmic Mountings, of which the following is a specification.

This invention relates to new and useful 10 improvements in ophthalmic mountings, and has particular reference to the construction of the center or bridging member of such mountings, and relates more particularly to the construction illustrated in 15 my process application which was filed August 1, 1917, and issued as Patent 1,302,548 of May 6, 1919, this application being filed as a division thereof.

The leading and principal object of the 20 present invention is the provision of a novel and improved manner of so constructing a spectacle bridge or other fitting for an ophthalmic mounting that the fitting shall have a reinforcement at the portion subject to greatest wear tending to make the wear of 25 the mounting as an entirety more uniform.

A further object of the invention is the provision of an improved construction particularly adapted for use in connection with 30 filled metals, which will provide an increased thickness of the outer or precious metal shell of the filled material at the greatest wearing points.

Other objects and advantages of my improved construction should be readily apparent by reference to the following specification taken in connection with the accompanying drawings, and it will be understood that I may make any modifications in 35 the specific details of construction shown and described within the scope of the appended claims without departing from or exceeding the spirit of my invention.

Figure I represents a front view of a mounting embodying my improvement.

Fig. II represents a plan view thereof.

Fig. III represents a plan of the blank in its initial stage.

Fig. IV represents a similar view of the blank in condition for forming.

Fig. V represents a longitudinal sectional view of the construction shown in Fig. IV.

Fig. VI represents a horizontal sectional view through the formed bridge.

Fig. VII represents a front view of a C bridge.

In the drawings, in which similar characters of reference are employed to denote corresponding parts throughout the several views, the numeral 1 denotes the frames adapted to contain the lenses 2 provided at 60 their outer ends with the temple or ear engaging members 3 for retaining the mounting on the face and being centrally connected by my improved bridge member. This improved bridge member is preferably 65 of the saddle type, comprising the arched portion 4 to fit the nose, terminating in the bends 5 having the forwardly extending arms 6 which are attached to the frames 1 or to suitable lens attachments.

In connection with the spectacle mounting it has been found in the past that the greatest wear on the mounting ordinarily occurs at the points of the bends 5 and that it is, therefore, desirable, particularly in the 70 case of filled material or material having a base metal core and precious metal shell thereon, to reinforce said material at the points 5. This in the past has been accomplished in various manners, as by the 75 securing of patches or the like on the bridge and subsequently reducing the several parts, and in other similar ways.

It is the purpose of my present invention, however, to provide a construction which 80 may be formed up from an ordinary strip of material without the use of any separate parts whatever, but which will possess the desired reinforcement where required. In the accomplishment of this I preferably 85 take a blank such as 7, centrally reduce it as at 8, leaving or forming during this operation the enlargements 9, which preferably terminate in additionally reduced portions 10, although this latter feature is not necessary in that the portions 10 may be left enlarged if preferred.

The great advantage of the formation of these enlargements should be clearly understood by reference to Figs. V and VI, in 100 which it will be seen that at the points of these enlargements the precious metal shell 9^a is much thicker than the shell at the point 8 or 10, this being due both to the fact that the shell was originally thick and was 105 thinned down during the reducing opera-

tion in producing the portions 8 and 10, and also to the fact that if the shell were at all softer than the base metal core 11 there would be a tendency during the reducing operation to crowd along the surface of the precious metal as the core is thinned down, while this crowded along material would naturally come to rest at the points 9 and aid in increasing the thickness of the precious metal at these points.

10 It will then be seen that it is merely necessary to form the bends 5 under metal the length of the portions 9 when the desired reinforcement will be provided.

15 While I have particularly illustrated this improvement as employed with a saddle bridge, it is equally applicable in the case of a C bridge such as illustrated in Fig. VII, frame, temple or other part of an ophthalmic mounting where it is desired to obtain specially reinforced coating at any particular point.

I claim:

1. A spectacle bridge comprising a central curved portion and enlargements

formed at the termini of said curved portion, as and for the purpose set forth.

2. A spectacle bridge comprising a central curved portion having its ends curved upwardly and enlargements formed at the curve between the ends and the central portion, as and for the purpose set forth.

3. A spectacle bridge comprising a central reduced portion, reduced terminal portions, and angularly bent enlargements intermediate the central and terminal portions whereby the enlargements provide additional material at the bends, substantially as and for the purpose set forth.

4. A spectacle bridge comprising a piece of filled stock having reduced central and terminal portions and having enlargements intermediate the central and terminal portions, the thickness of the precious metal case being greater at said enlargements than on the reduced central and terminal portions.

In testimony whereof I have affixed my signature.

PITT H. HERBERT.
